CLAIM

The ornamental design for a mounting clip bracket for all apertured board, as shown and described.

DESCRIPTION

FIG. 1 is a front perspective view of a mounting clip bracket for an apertured board showing my new design; FIGS. 2 and 3 are respectively top and bottom plan views thereof;

FIGS. 4 and 5 are respectively rear and front elevational views thereof;

FIG. 6 is a side elevational view thereof; the side opposite is a mirror image thereof.

FIG. 1

FIG. 2

FIG. 3

FIG. 4

FIG. 5

FIG. 6
